CLAIM

The ornamental design for a support arm as shown and described.

DESCRIPTION

FIG. 1 is a front, right, top perspective view of a support arm showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right bottom perspective view thereof;

FIG. 9 is a perspective view of the support arm of FIG. 1 in an angled configuration shown in a position of use with environmental subject matter; and,

FIG. 10 is a perspective view of the support arm of FIG. 1 shown in a position of use with environmental subject matter.

The broken lines and unshaded areas depict portions of the support arm that form no part of the claimed design.

The additional broken lines in FIGS. 9–10 depict environmental subject matter that forms no part of the claimed design.
